(No Model.)

S. BERGMANN.
EQUALIZER FOR ELECTRIC CURRENTS.

No. 398,121.

Patented Feb. 19, 1889.

UNITED STATES PATENT OFFICE.

SIGMUND BERGMANN, OF NEW YORK, N. Y.

EQUALIZER FOR ELECTRIC CURRENTS.

SPECIFICATION forming part of Letters Patent No. 398,121, dated February 19, 1889.

Application filed November 10, 1888. Serial No. 290,447. (No model.)

To all whom it may concern:

Be it known that I, SIGMUND BERGMANN, of New York, in the county and State of New York, have invented a certain new and useful Improvement in Equalizers for Electric Currents, of which the following is a specification.

In the accompanying drawings, Figure 1 is an end view of my invention. Fig. 2 is a plan or top view thereof, showing the coil-connections. Fig. 3 is a detail in section showing the transverse strips engaging the insulators. Fig. 4 shows a modification of the end castings or plates in which the coil ends are projected through insulators seated in openings in said plate. Fig. 5 is a transverse section of the same, and Fig. 6 is a sectional detail showing an insulator extended through an opening in the plate.

This invention has relation to improvements in equalizers for electric-light currents; and it consists in the construction and novel combination of parts, as hereinafter set forth, and pointed out in the appended claims.

It is found necessary in central-station work to have the ends of the various feeders at the same potential when the full load on the resistance is the same and having consequently the same drop; but when the load on the different feeders rises it is necessary to throw in circuit an artificial resistance to compensate for the difference of resistance caused by a varying load in the feeder. The function of the equalizer is to dissipate the additional energy caused by the drop of potential in this resistance in order to equalize the potential in the feeder. Heretofore these equalizers have been placed in or provided with wooden frames, which is found objectionable, inasmuch as they are so readily ignited and burned, endangering both life and property.

The object of the present invention is to provide a metal frame or casing for the resistance-coils of the equalizer, which are preferably insulated at their points of support.

In the wooden frames the degree of heat withstood is 300° Fahrenheit, and in the metal frame herein described the degree of heat may be increased to any practical degree less than that required to melt the metal.

A further object is to economize in space. An equalizer of the ordinary construction to carry one hundred ampères with twenty-volts

drop requires a frame twenty-four feet by twenty-four feet in cross-section by sixty feet in length, whereas in my improved frame the same energy can be dissipated in a space of eighteen feet by eighteen feet in cross-section and twenty-four feet in length, thus using less resistance-wire.

In the wooden frames the coils are usually connected by means of soft solder, as the low temperature made necessary by the use of wood never endangers or melts the connections. However, in the present instance, where a great degree of heat is expended, it is found necessary to connect the ends of the wires by brazing.

Referring by letter to the drawings, A designates a metal frame comprising the uprights B, which are preferably tubular, and the top and bottom castings C, having threaded openings to receive the threaded ends of the uprights, or the said parts may be otherwise secured together without departing from the spirit of my invention.

The uprights B are preferably hollow or tubular, as by this construction the weight of the whole construction is greatly diminished and the strength of said uprights is increased. The resistance-coils D have their ends projected through openings in the transverse metal strips E, and the said ends are preferably connected in their proper relations by brazing, as the degree of heat possible would destroy the solder connections heretofore employed.

The transverse strips E may have openings near their ends to engage a projection, a, on the insulators F, which are preferably seated in depressions a' in the end plates, as plainly shown in Fig. 3. These insulators F are preferably of an incombustible material—such, for instance, as porcelain, glass, or like material. A disk or washer, b, of asbestos or similar flexible non-combustible material, may be placed around the projections of the insulator beneath the lower face of the transverse strip E, so that the said insulators will not be endangered by any sudden shock received by the frame.

In Figs. 4 and 5 I have shown the end castings as made in plate form, with the insulators F seated in depressions therein, and in Fig. 6 I have shown the insulators as having

diverging sides, or in the form of a cone-frustum and extended through suitable openings in the plate. In the examples last described the insulators are perforated at b' for the passage of the coil ends.

It is to be understood that the formation of the frame may be varied to suit the requirements, as I only confine myself herein to an iron or other metal frame.

10 Having described my invention, what I claim is—

1. In an equalizer for electric currents, the combination, with the coils, of the metal frame comprising the uprights having the threaded ends, the end castings or plates having threaded openings engaging the uprights, and the insulators in said end castings or plates, substantially as specified.

2. In an equalizer for electric currents, the combination, with the coils, of the metal uprights, the metal end plates secured thereto having the openings, and the perforated insu-

lators in said openings receiving the ends of the coils, substantially as specified.

3. In an equalizer for electric currents, the combination, with the resistance-coils and the metal frame, of the transverse metal strips, the insulators between said strips and the frame, and disks of flexible material interposed between the insulators and the transverse strips, substantially as specified.

4. In an electrical equalizer, the combination, with the coils and the metal frame, of the transverse strips having the openings, the insulators between the strips and the frame having the projection, and the flexible washer surrounding said projection below the lower face of the transverse strips, substantially as specified.

SIGMUND BERGMANN.
